[57] CLAIM

The ornamental design for a wrap for goggles, as shown and described.

DESCRIPTION

FIG. 1 is a front elevational view of a wrap for goggles of conventional thickness showing our new design, the broken lines shown throughout the views being understood to represent conventional stitching;

FIG. 2 is an enlarged front elevational view thereof shown folded in the position of use; and,

FIG. 3 is a rear elevational view of FIG. 1.

FIG. 1

FIG. 2

FIG. 3
